WALL PAPER.

No. 20,328.

Patented Nov. 18, 1890.

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,328, dated November 18, 1890.

Application filed September 27, 1890. Serial No. 366,386. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of small flowers and leaves of the daisy arranged in a cluster, with small sprays of grass as a background, as represented in the accompanying photograph. The stems are intertwined and run vertically in curved lines 15 through the center of the cluster, with the leaves and flowers hanging from the upper ends of the stems. The clusters are printed in any desired color on tinted paper.

What I claim is—20 The design for wall-paper herein shown and described.

Witness my hand this 13th day of September, 1890.

CHARLES BOOZE.
